UNITED STATES PATENT OFFICE.

AUGUST MARIA BARTELMUS, OF BRUNN, CZECHOSLOVAKIA.

CHARGING DEVICE FOR BLAST FURNACES.

Application filed February 17, 1922. Serial No. 537,341.

To all whom it may concern:

Be it known that I, AUGUST MARIA BARTELMUS, a citizen of the Republic of Czechoslovakia, residing at Losselgasse 4, 5 Brunn, Czechoslovakia, have invented Charging Devices for Blast Furnaces, of which the following is a specification.

In the charging devices for producers, blast furnaces and the like as used hitherto, 10 in which the hopper is closed by a double valve, each valve has its own valve gear with its own hand lever, each valve being opened independently by operating its hand lever. The charging device according to 15 the present invention differs from these well-known charging devices by the two valves having a common opening gear and by the provision of fixing means adapted to hold one valve in the closed position or 20 an open position relatively to the other valve. The arrangement is substantially such that the large valve is suspended by means of a member adapted to be tensioned or slackened (a chain or the like), so that, 25 when the slackable member is tensioned, the valve is fixed. The tensioning of the slackable member (chain or the like) is possible independently of the opening movement, whereby the valve can be secured from opening 30 and kept in the closed position, while on the other hand it may be brought about by the opening movement, the lift of the opened valve being capable of being limited by the adjustment of the slackable mem- 35 ber, while the other valve as well can be moved into the open position by the fur- ther opening movement. Thus, either the small valve alone may be opened (central filling) or the large valve alone (marginal filling) or both the large and the small 40 valve (central and marginal filling). If the large valve be suspended from a plu- rality of slackable members, for instance three chains, each of which is adapted to be tensioned or adjusted independently to any required maximum amount, the charge 45 may be fed in at any side of the rim and the height of feed in the whole of the feed- ing space may be completely equalized.

50 In the accompanying drawing Figs. 1, 2, 3, 4 and 5 are sectional views through the hopper of a charging-device and through the valves of my invention, the valve-mech-

nism being shown in elevation, and the views showing different positions of the 55 valves.

The arrangement consists substantially of a double cone valve 1, 2, the smaller cone 1 of which forms the seating for the large cone 2, while the larger cone 2 closes the 60 hopper 3. The large valve 2 is suspended from chains 4 and rods 5 (for instance three chains and rods), of which each chain is adapted to be tensioned by tensioning means consisting of a crank 6 and a clamping de- 65 vice. The smaller valve 1, which forms the seating of the large valve 2, is suspended by means of a rod 9 to a hand lever 7, 8, which is pivoted in the hopper. When the chain tensioning cranks 6 are in the position I, 70 all the chains will be in tension and the large valve cannot be lowered and moved into the open position. Hence, on the hand lever 7, 8 being operated, only the small 75 valve is opened, causing coal or the like from the hopper to strike against the in- wardly directed sides of the cone 2 and to fall into the middle. When the chain ten- sioning cranks 6 are in the position II, the 80 chains 4 will be slack. Hence, on the hand lever 7, 8 being operated, first of all the large valve 2 will be opened, while the valve 1 remains closed owing to the weight of the valve 2. With the valve 2 in the open 85 position the charge will be fed around the sides only. This feeding around the sides only is only possible until the chains 4 are tensioned and the valve 2 is suspended from the tensioned chains. On the hand lever 7, 8 being further operated with the chains 90 in tension, the small valve 1 will also open, whereupon coal or the like can fall into the middle as well.

Thus the arrangement according to the invention makes it possible to charge in 95 three different ways, firstly feeding in the middle with the chains in position I, sec- ondly feeding around the sides only with position II and thirdly feeding in the mid- 100 le and around sides with position II, on the valve 1 being lowered further.

By the chain tensioning cranks 6 being placed in suitable intermediate positions, the proportion of feeding in the middle to feed- 105 ing around the sides may be regulated at will and, by tensioning only one or two

chains, the feeding may be carried out in any direction around the sides, as shown in Fig. 5.

On the closing movement taking place, 5 the small valve carries the large valve along with it, the small valve being kept closed by the weight of the large valve.

What I claim is:

1. In a charging apparatus for blast-furnaces, the combination with a hopper, a valve, having a central opening, adapted to contact with the marginal edge of the discharge end of said hopper, thus closing 10 passage between said valve and said marginal edge, a plurality of valve-suspension members pivotally connected to said valve, mechanism supported by said hopper for holding any one or more of said valve-suspension members in raised position, a 15 smaller vertically-movable valve for opening and closing the opening in the larger valve and adapted to support said larger valve when the latter's suspension-members are slackened, and means, also supported 20 by said hopper, for opening and closing said smaller valve.

2. In a charging apparatus for blast-furnaces of the character specified in claim 1, said manually-movable members comprising cranks rotatably carried by said hopper.

3. In a charging apparatus for blast-furnaces, the combination with a hopper, a valve, having a central opening, adapted to

contact with the marginal edge of the discharge end of said hopper, thus closing passage between said valve and said marginal edge, a plurality of valve-suspension members pivotally connected to said valve, mechanism supported by said hopper for holding any one or more of said valve-suspension members in raised position, a 45 smaller vertically-movable valve for opening and closing the opening in the larger valve and adapted to support said larger valve when the latter's suspension-members are slackened, and means, also supported 50 by said hopper, for opening and closing said smaller valve.

4. In a charging apparatus for blast-furnaces, the combination with a hopper, of a valve, having a central opening, adapted to 55 contact with the marginal edge of the discharge end of said hopper, thus closing passage between said marginal edge and said valve, a smaller valve for closing the central opening in said larger valve and movable independently of the larger valve to permit passage through said central opening, and mechanism for causing said valves to tilt in any one of a plurality of directions, so as to dump the contents of the hopper at any one of a number of points along 60 the marginal edge of the discharge end of the hopper, said mechanism including a plurality of suspension-members for the larger valve, and a plurality of individually- 65 and independently-movable members for selectively lowering or slackening said suspension-members.

AUGUST MARIA BARTELMUS.
